EUGENE GUSY, OF BUFFALO, NEW YORK.

SASH LOCK.

1,424,900.

Specification of Letters Patent. Patented Aug. 8, 1922.

Application filed July 7, 1920. Serial No. 394,516.

To all whom it may concern:

Be it known that I, EUGENE GUSY, a citizen of the United States, residing in Buffalo, in the county of Erie and State of New York, 5 have invented new and useful Improvements in Sash Locks, of which the following is a specification.

This invention relates to a sash lock which is more particularly designed for use in connection with a window having upper and lower sashes which are capable of sliding vertically and also swinging laterally with reference to each other in the window frame for the purpose of either opening or closing 10 the sashes for ventilation as well as permitting the sashes to be reversed so that either side of their glass panes may be washed or cleaned from the inner side of the room.

It is the purpose of this invention to provide a sash lock for windows of this character which will permit of either sliding these sashes vertically relatively to one another or swinging laterally relatively to one another to a limited extent, so as to permit of 15 ventilating the room and still prevent unlawful intrusion into the building from the exterior, said locking device being so organized that the same may be rendered inoperative and permit the sashes to slide vertically 20 relatively to each other to the fullest extent and also to completely reverse the sashes when this is required.

In the accompanying drawings:

Figure 1 is a fragmentary perspective view of a window showing my improved sash lock applied to adjacent parts of the upper and lower sashes which latter are capable of both a sliding and a pivotal motion within the window frame. Figure 2 is a 25 fragmentary vertical section, on an enlarged scale, of the opposing portions of two window sashes, equipped with my improved sash lock, this section being taken on line 2-2, Fig. 4. Figure 3 is a fragmentary vertical section, on an enlarged scale, taken on line 3-3, Fig. 2. Figure 4 is a fragmentary horizontal section taken on line 4-4, Fig. 2. Figures 5, 6 and 7 are detached perspective views of the main parts of my improved sash lock.

Similar characters of reference refer to like parts throughout the several views.

Although my improved sash lock is applicable to windows which may be variously constructed, it is more particularly designed 55 for a window having one or more sashes which are capable of both a sliding and a pivotal motion within the frame. In the particular instance shown in the drawings, the window to which my improved sash lock 60 is applied, comprises a frame 10 which is provided on the inner side of each of its uprights or stiles 11 with two vertical runways 12, 13. In these runways are slidably mounted hanging bars 14, 15 each of 65 which is movable vertically and preferably though not necessarily constructed of sheet metal. Within the frame are arranged the upper and lower sashes 16, 17, which are adapted to slide vertically past each other 70 and also are capable of turning about horizontal axes, this being accomplished by pivotally connecting each stile or upright bar of the upper sash about midway of its height with the central part of the hanging bar 14 in the outer runway by means of a horizontal pivot screw or pin 18 while each upright stile or bar of the lower sash is pivotally connected about midway of its 75 height with the central part of an inner hanging bar 15 by means of a horizontal pivot pin or screw 19, as shown in Figs. 1 and 4. By this construction both the upper and lower sashes may be raised and lowered within the frame in the usual manner 80 for ventilating or other purposes, and these sashes may also be rotated on their horizontal pivots for the purpose of reversing them, so that either side of the glass panes of the sashes can be cleaned from the 85 inside of the building.

My improved sash-lock which is associated with the upper and lower sashes of a window thus constructed, preferably comprises a horizontal guide tube 20 which is secured 95 transversely to the upper edge of the lower sash adjacent to one corner thereof by providing opposite sides of this tube with laterally projecting flanges 21 which receive fastening screws 22. On its upper side this 100 guide-tube is provided with a longitudinal slot 23 which preferably extends the full length thereof.

On the adjacent lower part of the upper

sash, preferably the lower end of one of its upright stiles, is mounted a vertical longitudinal guideway 24 which is provided with an undercut slot 25 preferably of T-shaped form in cross section, this longitudinal guide being preferably secured to the upper sash by means of screws 26 passing through the upper and lower ends thereof, as shown in the drawings, or by any other suitable means.

27 represents a horizontal locking rod which is preferably round in cross section and is capable of sliding lengthwise in the transverse guide tube and also capable of 15 rotating therein when in a certain position relatively thereto. At its outer end this locking rod is provided with a coupling head 28 preferably of T-shaped form, while its inner end is provided with a handle 29 forming a stop. The rear or inner part of the locking rod is provided with a longitudinal feather 30 but the periphery of its front or outer part is made substantially cylindrical. The coupling head on the locking rod is engaged with the T-slot of the vertical guideway by passing this head through the narrow part of the slot 25 while the long side of the head is parallel 25 with this slot, and after this head has passed into the wide part of this slot the head is turned so that the same extends across the narrow part of the slot, thereby coupling the vertical guideway and the upper sash to the locking rod and lower sash. When 30 the upper and lower sashes are thus connected, one or the other of the same may be moved vertically relatively to the other to a limited extent by reason of the fact that the coupling head at this time moves 35 vertically in the T-shaped slot of the vertical guideway. The length of this slot is only sufficient to permit of opening either of the sashes slightly at the top or the bottom of the frame as well as to permit both of the same to be shifted for producing a 40 slight opening at the top and the bottom of the frame. The length of this movement is however so determined that unauthorized persons attempting to gain an 45 entrance through such openings will find the same inadequate for the passage of their hands or instruments which may be employed in an attempt to break into the house. When swinging either one of the sashes 50 laterally with reference to the other, the locking rod will be drawn outwardly or forwardly in the horizontal guideway but the extent of this movement is limited by engagement of the stop or handle 29 engaging with the inner end of the horizontal 55 guideway. The range of movement of the opposing meeting edges of the upper and lower sashes is preferably so determined that only a comparatively narrow passage-

way is formed between the meeting portions 65 of the sashes for ventilating purposes, but not sufficient to permit the passage of the hands of a possible intruder or the passage 70 of tools which might be employed for burglarizing a house. While the two sashes 75 engage their meeting portions, as shown in Figs. 1, 2 and 4, the feather 30 of the locking rod is arranged wholly outside and in rear of the horizontal guideway, so that at this time the attendant in the 80 building or room is capable of freely turning the locking rod and couple or uncouple the two sashes for the purpose of rendering the same proof against unlawful intrusion from the outside, or to permit of fully 85 opening the sashes either by a vertically sliding or a rotary motion of the same relatively to each other. But when the sashes are turned relatively to each other, so as to separate their meeting portions one from 90 the other, then the feather 30 of the locking rod enters the slot 23 in the horizontal guideway, thereby preventing the locking rod from being turned and uncoupled from the upper sash if an attempt to do so 95 should be made by a person using a pair of nippers and gripping the outer part of the locking rod which is exposed between the meeting portions of the upper and lower sashes. It will thus be apparent that so 100 long as the meeting portions of the upper and lower sashes engage with each other, it is possible for the attendant to freely couple and uncouple these sashes, but when these sashes are swung into a more or less open position relatively to each other then the locking rod cannot be turned, especially not from the outer side of the building, so that by this means tampering with this lock 105 is frustrated.

This sash lock consists of comparatively few parts which can be produced at low cost, the same can be readily installed on the sashes of windows as now generally constructed, and when in use the same does not 110 detract from the neat and finished appearance of the window.

I claim as my invention:

A sash lock for connecting two sash members of a window which are slidable 115 vertically and also movable laterally relatively to one another, comprising a horizontal guide tube adapted to be mounted on one of said members and provided with a longitudinal slot, a vertical guide adapted to be 120 mounted on another of said members and provided with a longitudinal slot which is T-shaped in cross-section, and a locking rod slidable and rotatable in said guide tube and having a T-shaped head at its front end 125 which engages with said T-shaped slot and a stop at its rear end adapted to engage with the inner end of said horizontal guide, and

the inner part of the periphery of said rod being provided with a longitudinal feather adapted to engage the slot in said horizontal guide-way while the outer part of said periphery is cylindrical, said head sliding vertically in said T-shaped slot upon raising or lowering either of said sash mem-
bers, and said feather being adapted to engage the slot of said horizontal guide tube upon moving either of said sash members laterally relatively to the other, and said stop being adapted to limit such lateral movement.

EUGENE GUSY.
